UNITED STATES PATENT OFFICE.

CARL WINKLER, OF BERNE, SWITZERLAND.

MACHINE FOR CASTING STEREOTYPE PLATES.

Application filed September 23, 1922. Serial No. 590,191.

To all whom it may concern:

Be it known that I, CARL WINKLER, a citizen of the Swiss Republic, residing at Berne, in the Swiss Republic, have invented 5 new and useful Improvements in Machines for Casting Stereotype Plates, of which the following is a specification.

In machines for casting stereotype plates, in which the box, during the casting operation, is adjoined to a slot in the bottom of the metal melting pot, said box, which consists of a core and bed, must be moved away from the pot after a plate has been cast, in order to facilitate its opening for the 10 purpose of taking out the plate. These movements have been obtained up to the present by two systems of toggle levers moved by eccentrics. This construction, however, renders the machine somewhat 15 complicated, and it has the further drawback, that in the event of the coupling giving way, the box will fall away from the pot by gravity, before the casting operation is finished, thus uncovering the metal 20 outlet of the pot, with the result that the pot is emptied more or less on the floor of the shop.

According to my invention these drawbacks are overcome by rigidly attaching 25 the core to a tilting frame, in which the bed is adapted to slide, and by adapting this frame to be raised and lowered by a crank to press the box alternately against, and to move it away from, the pot, respectively, whilst by a second crank the bed is 30 moved in the frame, the movement being so timed that the box is closed, or opened, according as the frame is raised or lowered. The crank shaft is preferably turned by worm gearing.

In the accompanying drawing illustrating my invention:

Fig. 1 is a side elevation and port section of the frame carrying the box, showing the 45 melting pot in vertical section.

Fig. 2, a section on the line A—B in Fig. 1.

Fig. 3, a side elevation of the machine, showing the driving gear in section,

Fig. 4 is a plan of the driving gear alone,

Fig. 5, a section on A—B in Fig. 4, and

Fig. 6, a series of sketches showing parts of the driving gear in different positions.

The melting pot 1 has an outlet 3 controlled by a cock 2 (Fig. 1) and this opening adjoins the box, when the core 4 and

bed 5, forming this box, are brought into their raised position. The core 4 is fastened to the frame 6, whilst the bed 5 is adapted to be guided by a slot 7, when the box is opened, or closed. To press the closed box against the pot 1 the frame 6 is turned about the pin 8. This motion of the frame 6 is obtained from the shaft 9, which is journalled in the frame 6 and connected with the bed plate 12 by the crank pins 10 and links 11. These links 11 are resilient in a longitudinal direction, as will be seen from Fig. 1. When the shaft 9 turns, the frame 6, owing to its connection with the base 10 plate 12, is moved alternately up and down, and during each revolution, the box is 15 pressed resiliently once against the mouth 70 of the melting pot 1, and then moved away from same. In order to assure that the box, when it reaches the pot, is always 75 closed, but open again, when in the lower position, the bed adapted to slide in the slot 7 is moved up and down by means of the connecting rod 13 and crank shaft 14. 80

For the purpose of obtaining the necessary movements the motor 15 is provided, on the shaft of which the fly-wheel 16 is so mounted that it must rotate with but can slide longitudinally on said shaft. In one 85 end position the fly-wheel 16, which is constructed as part of a coupling, is brought into engagement, with the coupling part 17, which is fastened on the shaft 20, journalled at 18 and 19, and carries a worm 21, which 90 engages in the worm-wheel 22. This worm-wheel is seated loose, and the disc 23 as well as the disc 24 are fixed on the crank shaft 25, which, on one end, carries the crank 95 26, and, on the other end, the coupling sleeve 27, which can slide, but not turn, on said shaft. In the end position shown in Fig. 5 this sleeve communicates the rotation of the worm-wheel 22 to the shaft 25, consequently also to the crank 26 and disc 100 23, whilst in the opposite end position the sleeve 22 comes into engagement with a claw 28, the shaft 25, crank 26, and disc 23 being 105 then fixed in position.

By the toothed part of the disc 23 the 110 spur-wheel 29 is turned, which is keyed on the crank shaft 31 serving to move the box by means of the connecting rod 30. On this shaft is seated, further, the ratchet wheel 32, which, in every revolution of the worm-wheel 22, is turned periodically by the projections 33, 34 through two teeth.

In the intervals the ratchet wheel 32 is held by a pawl 36 engaging in the ratchet wheel 35, said pawl having a projection 37 sliding on the circumference of a flange 38 on the side of the worm-wheel, being thus held in contact with the ratchet 35. At the moment in which the ratchet wheel 32 is turned by one of the projections 33, 34, the necessary retreating movement of the pawl 36 is rendered possible by a recess 39 in the flange 38.

With the ratchet wheel 32 rotates the sleeve 40, which by means of the lever 41 moves the coupling 27 into engagement with, 16 and then away from, the worm-wheel 22 once for each rotation of the ratchet wheel.

Each time the coupling 27 comes into engagement with the worm-wheel, this wheel, which otherwise rotates loosely on the shaft 20 25 will move the following parts:

1. The crank 26, and, consequently, also the cock 2, from the position A through the position B into the position C (Fig. 6) the actual opening of the cock taking place 25 towards the end of the arc of 180° through which it is moved, thus from position B into position C.

2. The disc 23 keyed on the shaft 26, which, in turning from the position A into 30 position B (Fig. 6), turns by its teeth, the spur-wheel 29 and crank 31 through about 180° , thus closes the box and raises it towards the melting pot 1. Owing to the absence of teeth on a part of the circumference, 35 the disc 23 continues its rotation independent of the spur wheel 29 from the position B into C, until the crank 26 has finished its rotation of 180° and the cock is open. Thereafter the coupling 27 is moved into the opposite end position, whereupon the shaft 25 is again fastened.

In the position C, in which the box is filled with melted metal from the pot and the plate thus cast solidifies, the parts remain stationary (about 12 seconds) until the ratchet wheel 32 has been turned through a complete revolution by the projections 33, 34. The coupling 27 is then brought into engagement with the worm-wheel 22 again, and, by so doing, the shaft 25 is turned through 180° , thus out of the position C through D into A, which, as long as the non-toothed part of the segment is directed towards the stationary spur-wheel 29 (position C), causes the cock to be closed by the crank 26, and then, by the engagement of the toothed part of the segment with the spur-wheel 29, rotates the crank 31 by which the box is lowered and opened, to enable the cast plate to be taken out by hand.

In the position B, C and D, in which the spur-wheel 29 is not held any more by engagement with the toothed part of the disc 65 23 the concave part 42 engages the circum-

ference of the disc 24, so that it is not possible for the box to fall away from the pot.

To enable the coupling 16, 17 to be put in and out of gear the lever 47 is provided, which, in the lowered position, moves the fly-wheel 16, by means of the fork 45, against the stationary coupling part 17, thus putting the machine into action for casting. By the same movement the disc 46, will be moved away from the coupling part 17. In the lower position the lever 43 will be held by the pawl-lever 47, which, for this purpose, is provided with a tappet 48 adapted to engage over the tappet 49 on the lever 43. As soon as the casting operation is completed, and the disc 23 and spur-wheel 29 reach the position A (Fig. 6) the pawl-lever 44, either by hand, or by a tappet on the ratchet wheel 32, is moved out of engagement with the lever 43, so that the latter rises, and the fly-wheel 16 is moved away from the coupling part 17 by the spring 50.

What I claim and desire to secure by Letters Patent of the United States is:—

1. A casting machine for stereotype plates, 90 and the like, comprising in combination, a melting pot, a tilting frame, a box core rigidly fastened to said frame and adapted in the tilted up position of said frame to press against said pot, a bed adapted to slide in said frame, a crank to tilt said frame up and down, and a crank to move said bed in said frame, substantially as, and for the purpose, set forth.

2. A casting machine for stereotype plates, 100 and the like, comprising in combination a melting pot, a tilting frame, a box core rigidly fastened to said frame and adapted in the tilted up position of said frame to press against said pot, a bed adapted to slide in 105 said frame, a crank to tilt said frame up and down, a resilient support for said crank, and a crank to move said bed in said frame, substantially as, and for the purpose set forth.

3. Casting machine for stereo-plates, and the like, comprising in combination, a melting pot, a cock adapted to open and close an opening in said pot, a tilting frame, a box core rigidly fastened to said frame and 115 adapted in the tilted up position of said frame, to press against said pot, a box-bed adapted to slide in said frame, a crank shaft adapted to turn said cock, a partially toothed disc fastened on said shaft, a spur-wheel of 120 smaller diameter adapted to be turned periodically by said partially toothed disc, a crank-shaft carrying said spur-wheel and adapted by the periodical motion to move said box in the closed casting position and open position for taking out a cast plate 125 respectively, substantially as, and for the purpose, set forth.

4. Casting machine for stereo-plates, and the like, comprising in combination, a melt- 130

ing pot, a cock adapted to open and close an opening in said pot, a tilting frame, a box core rigidly fastened to said frame, a box-bed adapted to slide in said frame, a 5 crank to tilt said frame up and down, a crank to move said bed in said frame, a first shaft containing said crank, a second crank shaft adapted to open and close said cock, a tooth-wheel loosely mounted on said 10 second crank shaft, mechanism moved by said toothed wheel and adapted to periodically connect said toothed wheel with said shaft, a third shaft, to turn said first crank shaft, and means to periodically turn said 15 third shaft by said second crank shaft, substantially as, and for the purpose, set forth.

5. Casting machine for stereo-plates, and the like, comprising in combination, a melting pot, a cock adapted to open and close 20 an opening in said pot, a tilting frame, a box core rigidly fastened to said frame, a box-bed adapted to slide in said frame, a crank to tilt said frame up and down, a crank to move said bed in said frame, a first 25 shaft containing said cranks, a second crank shaft adapted to open and close said cock, a tooth-wheel loosely mounted on said second crank shaft, mechanism moved by 30 said toothed wheel and adapted to periodically connect said toothed wheel with said shaft, a claw to hold said second crank shaft stationary when the connection with the toothed wheel is undone, a third shaft to 35 turn said first crank shaft, and means to periodically turn said third shaft by said second crank shaft, substantially as, and for the purpose, set forth.

on said second crank shaft, and a concave piece on said third shaft adapted in a corresponding angular position to engage with said disc, substantially as, and for the purpose, set forth. 35

6. Casting machine for stereo-plates, and the like comprising in combination, a melting pot, a cock adapted to open and close an opening in said pot, a tilting frame, a box core rigidly fastened to said frame, a box-bed adapted to slide in said frame, a crank to tilt said frame up and down, a crank to move said bed in said frame, a first shaft containing said cranks, a second crank shaft adapted to open and close said cock, a tooth-wheel loosely mounted on said second crank shaft, mechanism moved by 40 said toothed wheel and adapted to periodically connect said toothed wheel with said shaft, a claw to hold said second crank shaft stationary when the connection with the toothed wheel is undone, a third shaft to 45 turn said first crank shaft, and means to periodically turn said third shaft by said second crank shaft, substantially as, and for the purpose, set forth. 50

In testimony whereof I have signed my name to this specification in the presence of two subscribing witnesses. 55
